CLAIM

The ornamental design for a glove, as shown and described.

DESCRIPTION

The patent file contains at least one drawing executed in color. Copies of this patent with color drawings will be provided by the Office upon request and payment of the necessary fee.

FIG. 1 is a top perspective view of a glove showing our new design according to a first embodiment;

FIG. 2 is a top view thereof;

FIG. 3 is a bottom view thereof;

FIG. 4 is a top perspective view of a glove showing our new design according to a second embodiment;

FIG. 5 is a top view thereof; and,

FIG. 6 is a bottom view thereof.

The broken line text and icons, and the white areas bounded by broken lines, form no part of the claimed design. The remaining broken lines in the drawings illustrate stitching that forms part of the claimed design.

The figures show a left hand glove. Apart from the broken line text and icons (which is not mirrored), the right hand glove, which is not depicted in the drawings, is a mirror image of the left hand glove of FIGS. 1-3 and 4-6, respectively.

1 Claim, 6 Drawing Sheets
